UNITED STATES PATENT OFFICE.

ALBERT S. MOFFAT, OF BELMONT, MASSACHUSETTS, ASSIGNOR TO KUNZ-GARNISS COMPANY, A CORPORATION OF MASSACHUSETTS.

TELEPHONE RECEIVER.

1,152,536.

Specification of Letters Patent. Patented Sept. 7, 1915.

Application filed August 8, 1914. Serial No. 855,890.

To all whom it may concern:

Be it known that I, ALBERT S. MOFFAT, residing at Belmont, in the county of Middlesex and Commonwealth of Massachusetts, a citizen of the United States, have invented 5 certain new and useful Improvements in Telephone-receivers, of which the following is a full, clear, and exact description.

This invention has to do with telephone 10 receivers used in connection with loud-speaking telephones, and has for its purpose the effecting of improvements in details of construction as hereinafter set forth, and illustrated in the drawings forming part of 15 this specification, in which—

Figure 1 is a central longitudinal section of a receiver embodying my improvements. Fig. 2 is a detail view on a larger scale of 20 the laterally adjustable pole piece. Fig. 3 is a face view of the longitudinally adjustable pole piece. Fig. 4 is an end view of 25 the same and of its windings. Fig. 5 is a perspective view of the armature.

The reference numeral 1 designates the 30 receiver case, preferably cylindrical in formation, and having a cap 2 suitably affixed thereto, as by the screw-threaded flange 3. Fitted tightly within the upper part of said 35 case is a cup 4 between which and said cap is secured the diaphragm 5 by means of rubber rings 6, said diaphragm being preferably composed of mica. To said cap is secured a horn 7 or other means for the direction of the sound-waves.

35 Diametrically across the case is secured a bar 10, preferably held by screws 11 and by a leg 12 attached to the bottom of the case. Said bar has a transversely disposed slot 13 in which slidably fits the adjustable 40 slot 14 whose stem 15 is threaded and extends out through the case-bottom. The pole piece 14 is surrounded by the oblong core 20 upon which the coil 21 is wound, and is preferably slidable therein, said core and 45 coil being fastened in any suitable manner to the bar 10. For thus moving said pole piece, in order to present it as near to the armature as possible, without danger of actual contact, and thereby to produce the

50 maximum effect upon the armature and hence upon the diaphragm, a sleeve 16 is provided for the stem 15 and formed with a shoulder 17 bearing against the interior of the case 1. This sleeve being threaded both 55 internally and externally to fit said stem

and to enter a nut 19, the latter being outside the case, the proper rotation of both nut and sleeve will present the pole piece at the desired point of adjustment. Slidable on said bar 10 is the pole piece 22 held 60 in place thereon by a small set screw 23, and resting against the outer end of the pole piece is an end of the armature 24. From the opposite end of the latter extends a slender elbow 25 attached to the center of 65 the diaphragm by small nuts 26.

When pulsatory current is delivered to the coil 21, as by talking into a transmitter at the other end of the line, the pole piece 14 variably attracts the armature in the usual 70 way and thereby vibrates the diaphragm. Since the point of attachment to the diaphragm is nearly twice as far from the pole 75 22 as is the pole 14, the amplitude of vibration imparted to the diaphragm will be correspondingly magnified, and the sound emitted thereby will be far louder than would be the case were said point of attachment directly over the pole piece 14. By adjusting the pole 22, which serves as the fulcrum for 80 the armature, nearer to the coil, the loudness of sound will be still further increased and vice versa.

Rising from the pole piece 22 is a slight lug 27 fitting in a slot or groove 29 in the 85 armature 24. The engagement of said lug and groove serves to keep the armature laterally in place on the said pole piece, while permitting the adjustment of the latter relative to the pole-piece 14.

It is evident that the magnetic attraction between the pole piece 22 and the contacting end of the armature will retain the latter in place thereon when there is any current in circuit, but when the receiver is being shipped 90 or put in storage, such attraction would be absent and there would be danger of the armature's swinging laterally on the elbow 95 25 at its point of attachment to the diaphragm as a center, and so becoming badly 100 displaced.

What I claim is:

1. A telephone receiver comprising an electromagnet having its poles in the same transverse plane, an armature, and a diaphragm centrally connected with one end of said armature, the end of the armature farther removed from said diaphragm being 105 slidably supported by one of said poles and its other end being in the field of the other 110

2. A telephone receiver comprising an electromagnet having its poles in the same transverse plane, an armature, and a diaphragm centrally connected with one end of said armature, the other end of the armature being supported by one of said poles, the latter being adjustable toward and from the other pole, and it and the armature having means for keeping the armature from lateral displacement.
3. A telephone receiver comprising an electromagnet having its poles in the same transverse plane, an armature, and a diaphragm centrally connected with one end of said armature, the other end of the latter having a longitudinally disposed groove, one of said poles being adjustable toward and from the other pole and having a lug engaging said groove.
4. A telephone receiver comprising a diaphragm, a case supporting the same, an armature parallel with the diaphragm and connected at one end with the latter, a pole piece supported rigidly by the case with its field close to the end of the armature connected with the diaphragm, windings about said pole piece, a second pole piece parallel with and in magnetic connection with the first pole piece and adjustable toward and from the same, the first named pole-piece being tubular, a core longitudinally movable in the tubular pole-piece, and means operative exteriorly of the case for longitudinally adjusting the core, the end of the armature not connected with the diaphragm being slidably supported by the second-named pole-piece.
5. A telephone receiver comprising a horse shoe magnet, a fulcrumed armature, and a diaphragm connected with one end of said armature, said magnet having a longitudinally adjustable pole presented to the end of said armature connected with said diaphragm, the said adjustment being accomplished by means of a threaded stem projecting from the pole, a shouldered sleeve internally and externally threaded and turning on said stem, and a nut on said sleeve, the receiver having a case penetrated by said stem and sleeve, the shoulder of said sleeve abutting against the inner surface of the case, and said nut abutting against the outer surface thereof.
- In testimony that I claim the foregoing invention, I have hereunto set my hand this 7th day of August, 1914.
- ALBERT S. MOFFAT.
